[57] CLAIM

The ornamental design for an interacting chair unit, as
shown and described.

DESCRIPTION

FIG. 1 is a front perspective view of a chair unit showing
my design;

FIG. 2 is a front elevation view thereof;

FIG. 3 is a right side elevation view thereof;

FIG. 4 is a left side elevation view thereof;

FIG. 5 is a rear perspective view thereof;

FIG. 6 is a rear elevational view thereof;

FIG. 7 is a top plan view;

FIG. 8 is a bottom plan view;

FIG. 9 is a perspective view of a second embodiment of
the chair unit being the fitting together of two units;

FIG. 10 is an elevational view of the embodiment;

FIG. 11 is an elevational view of one side of the embodi-
ment, the opposite side being identical;

FIG. 12 is a top plan view of the embodiment; and,

FIG. 13 is a bottom view of the embodiment.
